UNITED STATES PATENT OFFICE.

CHARLES MILTON KESSLER, OF LOUISVILLE, KENTUCKY.

DESIGN FOR A DRESSER.

SPECIFICATION forming part of Design No. 35,912, dated May 13, 1902.

Application filed April 7, 1902. Serial No. 101,849. Term of patent 7 years.

To all whom it may concern:

Be it known that I, CHARLES MILTON KESSLER, a citizen of the United States, residing at Louisville, in the county of Jefferson and State of Kentucky, have invented and produced a new and original Design for Dressers, of which the following is a specification, reference being had to the accompanying drawings, forming a part thereof.

10 Figure 1 is a front elevation of a dresser, showing the new design. Fig. 2 is a side or end elevation of the same. Fig. 3 is a bottom plan view thereof.

15 The leading feature of the design consists in the frame or supporting structure of the dresser.

Upon reference to the drawings it will be seen that the frame comprises in its design a series of uprights 1, arranged adjacent to the 20 four corners of the dresser, as shown in Fig. 3, the said uprights being joined at a short distance above their lower ends by longitudinal bars 2 and cross-bars 3, the bars 2 and 3 being located in the same horizontal plane.

25 The uprights 1 are further connected at a higher point by cross-bars 4, similar to those 3, all of the cross-bars 3 and 4 having their end portions curved, as shown at 5, so as to offset the central portions of the cross-bars

30 and give what is known in the art as "swell" ends or sides to the dresser. The space between the upper and lower cross-bars and the front and rear uprights 1 is partially filled by scrollwork, as illustrated in Figs. 1 and 2,

35 each scroll comprising a centrally-arranged rosette 6, with radiating bars or spokes 7, the ends of which are bifurcated or carved in opposite directions in semicircular form, as shown at 8, the extremities of the portions 8 40 being brought together and connected by

bands or collars 9. The portions of the scroll-work abutting against the uprights 1 and the cross-bars 3 and 4 are connected with said parts by rings or collars 10. The entire scroll-work is bent or dished from the inner side to 45 conform to the curvature of the cross-bars 5. At a suitable distance above the cross-bars 4 is the usual shelf or leaf 11, the ends of which are rounded and have attached to the lower side thereof a series of vertical parallel rods 50 12, which extend downward to the upper cross-bars 4 and connect therewith by means of rings or collars 10 and 13. Between the legs 1 and between the lower longitudinal bars 2 and the shelf or leaf 11 are arranged drawers 55 14, having at their ends angle-irons 15, which rest upon parallel strips 16 on the uprights 1. Said uprights extend below the lower cross-bars 3 and form the supporting-legs of the dresser. The standards 17, of ogee, extend 60 upward from the shelf or leaf 11, and a mirror, mounted in a mirror-frame 18, is interposed between the standards 17 and surmounted by an ornamental diamond-shaped cap 19, connected with the mirror-frame by ornamental 65 scrollwork 20. The standards 17 are shown as connected by a horizontal strip 21, extending along the rear edge of the shelf or leaf 11. Diagonal bars 22 lie beneath the series of drawers and have their extremities connected 70 with the lower longitudinal bars 2, as shown in Fig. 3.

Having thus described the design, what I claim is—

The design for a dresser as herein shown 75 and described.

CHARLES MILTON KESSLER.
